FIG. 2

FIG. 1

George E. Fearn
INVENTOR

BY
Elton Smith
ATTORNEY

UNITED STATES PATENT OFFICE

146,900

DESIGN FOR A PIN OR SIMILAR ARTICLE

George E. Fearn, New York, N. Y., assignor to Kaufman-Ruderman Co. Inc., New York, N. Y., a corporation of New York

Application April 6, 1946, Serial No. 128,350

Term of patent 3½ years

(Cl. D45—19)

To all whom it may concern:

Be it known that I, George E. Fearn, a citizen of the United States, residing at New York, in the county of New York and State of New York, have invented a new, original, and ornamental Design for a Pin or Similar Article, of which the following is a specification, reference being had to the accompanying drawing, forming part thereof.

In the drawing:

Fig. 1 is a front elevational view of a pin showing my new design; and

Fig. 2 is a side view thereof.

I claim:

The ornamental design for a pin or similar article, as shown.

GEORGE E. FEARN.
